(57) **CLAIM**

The ornamental design for a large row crop tractor hood, as shown and described.

DESCRIPTION

FIG. 1 is a perspective view of a large row crop tractor hood showing our new design.

FIG. 2 is an elevational view of the large row crop tractor hood design of FIG. 1.

FIG. 3 is an enlarged view of the area 2A of the large row crop tractor hood of FIG. 2.

FIG. 4 is an elevational view of the large row crop tractor hood design of FIG. 1.

FIG. 5 is an enlarged view of the area 3A of the large row crop tractor hood of FIG. 3.

FIG. 6 is a plan view of the large row crop tractor hood design of FIG. 1.

FIG. 7 is a bottom view of the large row crop tractor hood design of FIG. 1.

FIG. 8 is an enlarged view of the area 5A of the large row crop tractor hood of FIG. 5.

FIG. 9 is an enlarged view of the area 5B of the large row crop tractor hood of FIG. 5.

FIG. 10 is a front view of the large row crop tractor hood design of FIG. 1.

FIG. 11 is a rear view of the large row crop tractor hood design of FIG. 1.

FIG. 12 is an enlarged view of the area 7A of the large row crop tractor hood of FIG. 7; and,

FIG. 13 is an enlarged view of the area 7B of the large row crop tractor hood of FIG. 7.
